(57) **CLAIM**

The ornamental design for a pipe inspection camera, as shown and described.

DESCRIPTION

FIG. 1 is a bottom, rear and left side perspective view of a pipe inspection camera, showing my new design;
FIG. 2 is a top, front and right side perspective view thereof;
FIG. 3 is a bottom, rear and right side perspective view thereof;

FIG. 4 is a bottom and front perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.
